UNITED STATES PATENT OFFICE.

ABRAHAM P. RINDSKOPF AND HENRY P. RINDSKOPF, OF BROOKLYN,
NEW YORK.

DESIGN FOR A GARMENT-SUPPORTER.

SPECIFICATION forming part of Design No. 18,205, dated March 27, 1888.

Application filed January 25, 1888. Serial No. 261,922. Term of patent 7 years.

To all whom it may concern:

Be it known that we, ABRAHAM P. RINDSKOPF and HENRY P. RINDSKOPF, both of Brooklyn, in the county of Kings and State of New York, have invented and produced a new and original Design for the Clip of a Garment-Supporter, of which the following is a specification.

Reference is to be had to the accompanying drawing, forming a part of this specification, in which the figure is a plan view of our newly-designed garment-supporter.

The leading feature of our design consists of a circular edge joining at one portion thereof two converging edges, which meet, forming a V, the space of which joins a circular space. a represents the circular edge, which terminates at rounded corners b b. The corners b b merge gradually each into a diagonal line or edge, c c. The two edges face each other and converge together, forming a V, which opens into the circular space compassed by the circular edge a. The outer edge of the supporter, surrounding the circular edge a, forms an el-

lipse, d, the side edges of which merge into the 25 diagonal or converging lines or edges e e, which are parallel with the converging edges c c. The edges or lines e e merge into the curved end or edge f at the tip or bottom of the supporter. The curves or circles a d are not concentric and are farthest apart at the head or top of the supporter, and between the upper oval, d', of the ellipse d and the circular edge a opposite the V appear the two parallel lines i i, joined by short end lines, i', as shown 30 35 clearly in the accompanying drawing.

We claim—

The design for the clip of a garment-supporter herein shown and described, the same consisting of the ellipse d, circle f, and the 40 converging lines e e, joining the circle f with the ellipse.

ABRAHAM P. RINDSKOPF.
HENRY P. RINDSKOPF.
